UNITED STATES PATENT OFFICE.

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

CURLING IRON.

Application filed January 23, 1926. Serial No. 33,193.

The objects of the present improvements are primarily to produce a detachable connection between the heating iron or barrel and the curling clamp, which will enable 5 the user of the device to remove the latter from the former and restore it quickly and easily and without the necessity of observing the particular position of the parts, and which will hold the parts securely in position 10 and control their relative movements with certainty and precision. Other objects will be apparent to those familiar with devices of this character.

The improvements are illustrated in the 15 accompanying drawings, in which Fig. 1 is a side elevation of an electric curling iron embodying the improvements; Fig. 2 is a side view, partly in longitudinal section of the parts shown in Fig. 1, indicating 20 open and closed positions, with the handle broken away; Fig. 3 is a side view of the curling clamp detached; Fig. 4 is a view of the end of this device next to the handle, and its connections; Fig. 5 is an enlarged 25 detail in perspective of the polygonal butt of the iron; and Fig. 6 is a front view of the butt of the iron proper with the iron in vertical section on the line 6-6 of Fig. 5.

In the illustration of the invention shown 30 in the drawings the handle 1 has the curling-iron proper 2 mounted thereon and secured to one end thereof by means of a collar 3. In this instance the iron is cylindrical in form, with its outer end closed, and 35 is adapted to enclose a heating coil, which may connect through the interior of the handle with a plug 4 or other means for supplying it with electric current. The butt of the iron 5 is polygonal in cross section 40 where it merges in the iron through a rounded annular shoulder 5^a and is of conical form, increasing in diameter on curved lines toward the handle, where its surface becomes annular and terminates in an abrupt 45 shoulder 6 connecting with the collar 3.

The clamping member 7 is of the usual 50 concave-convex form, is substantially co-extensive longitudinally with the iron or barrel 2, and is adapted to clamp the hair thereon. It is pivoted on an open slide 8, and is 55 constantly pressed against the iron by means of a spring wound around its pivot pin 9 as shown at 10, and having one portion 11 extending upwardly and pressing against the

handle 13, and another, 12, extending backwardly and pressing against the butt of the iron. The spring is formed by bending a single piece of spring wire, or the like, to form a loop, and then winding it double around the pivot. The upper ends of the 60 spring are held under the downwardly extending portion 15 of the plate 14, and between it and the concave underside of the arm 13. The plate 14 is secured to a non-heat conducting operating button 16 by 65 means of a rivet 17 passing through the plate, the top portion of the arm and the button, and having its head countersunk. The outer extremity of the portion 12 of the spring is bent to form a latch 18 with 70 a releasing extension 19, so that when the slide 8 is pressed against the butt this latch will securely engage the shoulder 6, and so that it can be released, when it is desired to 75 remove the hair clamp or move it on the iron, by pressure of the thumb or finger of the operator.

The slide 8 is also polygonal in form and corresponds to the outer part of the iron butt, upon which it fits rather snugly, so as to 80 prevent relative lateral movement of the parts of the curler, having a rounded annular shoulder 8^a corresponding to the similar shoulder 5^a of the iron butt. At the same time when it is desired to connect the clamp 85 and the iron it is only necessary to press the latter against the butt so that the slide passes over the complementary part of the butt and the latch snaps over the shoulder 6, without the necessity of locating the position of the parts. This important advantage 90 is due to the fact that the slide or sleeve 8 will slip over the butt and take its position thereon, rotating slightly, if necessary when pressed against the butt, to bring the parts 95 into the proper relative positions circumferentially, for telescoping. But when these parts are telescoped they are held securely against relative rotary movement.

It will be seen that the spring is so constructed and arranged that it not only acts as a clamp actuating spring and a latch, but also acts as a stop limiting the downward movement of the arm, and that its releasing means is integral therewith. It will also be seen that the clamp may be quickly removed and replaced and that no care is necessary in the making of these adjustments since 105

pressure on the spring release 19 releases the spring and pressure on the arm 13 causes it to engage again and unite the two parts of the curler, and in connecting these parts after separation it is not necessary to observe the position of the slide 8 or the iron.

From the foregoing it will be seen that the polygonal butt or ferrule and the sleeve of similar shape with their beveled outer ends form a connection which may be made by simply pressing the latter against the former with only a slight rotary movement, if any, to cause the parts to snap "home", the flat opposing faces of the butt merging in the annular bevel 5^a providing a guide for the sleeve which will cause it to assume its proper position. The connection also furnishes a secure and easily manipulated locking shoulder and holding the parts securely against movement in all directions.

I claim:

1. The combination of an elongated heating member, a hair clamping member mounted on the heating member and movable to and from the same, an operating arm connected with the clamping member, and a connection between the heating and the clamping members to lock the said two members against relative and rotary movement, said connection comprising a polygonal portion at the inner end of the heating member, a part having similar form on the clamping member adapted to fit thereon and means at the outer end of said polygonal portion to laterally guide the connection on the clamping member to a position of coincidence when moved longitudinally onto the polygonal portion.

2. The combination of an elongated heating member, a hair clamping member mounted on the heating member and movable to and from the same, an operating arm connected with the clamping member, and a connection between the heating and the clamping members to lock the said two members against relative and rotary movement, said connection comprising a polygonal portion at the inner end of the heating member, a part having similar form on the clamping member adapted to fit thereon and means to guide the parts of the connection to a position of coincidence when brought into association with each other.

3. In a device of the character described the combination of an elongated heating member, a hair clamping member pivoted thereon, an annular shoulder on one member extending beyond its outer surfaces and a spring latch member carried by the other confined under compression between the two members and engaging the said shoulder when the said members are assembled in nor-

mal position, said spring latch member having at its enlarged end a substantially right angular projecting extension terminating at 65 a point forward of the point of engagement of the spring latch whereby said latch may be moved from engagement with the shoulder by a forward pressure on the free end of said extension.

4. In a device of the character described the combination of an elongated heating member, a hair clamping member pivoted thereon, an annular shoulder on one member and a spring latch member carried by the other confined under compression between the two members and engaging the said shoulder when the said members are assembled in normal position, said spring latch member having an extension whereby it may be moved from engagement with the shoulder, and said extension being in the path of a portion of the clamping member and adapted to act as a stop for limiting the movement of the said member.

5. The combination of an elongated heating member, a hair clamping member, a member adapted to slide on the former, a pivot on which the clamping member is mounted on the slideable member and a spring member mounted on said pivot and having portions engaging the heating and the clamping members, said spring being confined under pressure between portions of said heating and clamping members, and having an angular projection on one portion extending away from the member with which said portion is in contact and toward the other portion substantially at right angles to the said other portion and into its path.

6. The combination of a heating member, a clamping member and a sliding member on said heating member on which the clamping member is mounted, said heating member having a portion polygonal in cross section, and said sliding member having a portion formed to coincide with said polygonal portion of the heating member and to be positioned thereon, whereby the said parts are held against relative rotary movement, said polygonal portion of the heating member having a conical portion between it and the adjacent surface of the heating member merging in said surface and in the polygonal portion, whereby the corresponding portion of the sliding member will be guided laterally on moving longitudinally thereon to a position of coincidence.

Witness my hand this 7th day of January, 1926, at the city of Milwaukee, in the county of Milwaukee, State of Wisconsin.

EDWIN A. RUTENBER.
